J. D. DUNN,
COMBINATION COOKING UTENSIL,
APPLICATION FILED FEB. 10, 1917.

1,288,533.

Patented Dec. 24, 1918.

J. D. Dunn.

Shattuck, Attorney

UNITED STATES PATENT OFFICE.

JAMES D. DUNN, OF NEW ORLEANS, LOUISIANA.

COMBINATION COOKING UTENSIL.

1,288,533.

Specification of Letters Patent. Patented Dec. 24, 1918.

Application filed February 10, 1917. Serial No. 147,871.

To all whom it may concern:

Be it known that I, JAMES D. DUNN, a citizen of the United States, residing at New Orleans, in the county of Orleans and State 5 of Louisiana, have invented certain new and useful Improvements in Combination Cooking Utensils, of which the following is a specification.

This invention relates to improvements in 10 culinary apparatus adapted to be employed in connection with gas or oil stoves or like heating devices, and has for one of its objects to provide a simply constructed device in which the parts may be disassembled for 15 shipment or storage, and assembled when required by any person without previous skill or knowledge.

Another object of the invention is to provide a device of this character adapted for 20 use by campers, explorers and the like and may be disassembled and packed with the other camp equipage.

With these and other objects in view, the invention consists in certain novel features 25 of construction, as hereinafter shown and described and then specifically pointed out in the claims; and in the drawings illustrative of the preferred embodiment of the invention—

30 Figure 1 is an elevation, partly in section, of the improved device applied to a heater in which oil is employed as a fuel.

Fig. 2 is a plan view with the shell in section on the line 2—2 of Fig. 1.

35 Fig. 3 is a detached perspective view of one of the shelves employed in connection with the form of the device illustrated in Figs. 1 and 2.

Corresponding and like parts are referred 40 to in the following description and indicated in all the views of the drawings by the same reference characters.

The improved device includes a body or shell represented as a whole at 10, and adapted 45 to be supported over a heater 11 of any suitable construction.

The shell 10 is open at the upper end and provided with a suitable closure comprising 50 a supporting member or body portion 17 and a depending flange 18 which fits within the upper edge of the shell. The body portion 17 is provided with a plurality of apertures 19, and pivoted at 20 upon the body 17 is a cut-off plate 21 having apertures 22 corresponding to the apertures 19 and adapted

to register therewith when the cut-off member is disposed in one position. The cut-off plate when rotated slightly upon its pivot will locate the openings 22 opposite the solid unperforated portion of the body 17. By 60 this means air may be admitted through the top to any required extent within the range of the openings 19—22. The down draft may thus be controlled as required.

Slidably disposed through the body portion 65 17 of the top are the down turned ends of a handle 23, the lower ends of the handle being enlarged laterally to prevent the handle from being withdrawn. Thus when released the horizontal portion of the handle 70 23 will lie in close engagement with the upper face of the body 23 and out of the way, and when the closure is to be removed the handle 23 may be elevated until the enlargements 75 24 engage the lower face of the closure.

Supported by the inner walls of the shell 10 are transverse supporting bars 25, the latter being located some distance below the upper open end of the shell. Any required 80 number of the bars may be employed but generally two will be sufficient, arranged to cross each other, as shown in Fig. 2, and with down turned ends to receive holding rivets 26 when rivets are employed to secure the shell. 85

The bars are riveted together at 27 where they cross each other as shown. The space between the bars 25 and the open upper end of the shell constitutes the chamber in which the vessels containing the food to be cooked 90 are deposited or supported. These vessels may be of any required shape, either a single vessel conforming substantially to the outlines of the shell, or formed in a plurality of parts and arranged side by side within 95 the cooking chamber. In Fig. 1 two semi-circular vessels are represented at 28. The upper end of the shell may be also utilized to support an ordinary kettle or like cooking vessel by detaching the closure 17—18. 100

Detachable shelves may likewise be employed in connection with the shell 10, each comprising a body portion 31 having supporting brackets connected thereto, each bracket comprising an upper horizontal 105 member 32 riveted or otherwise attached to the shelf, a depending portion 33 bearing against the outer face of the shell, a diagonal brace 34, and a hook-like extension 35, the latter passing through a suitable 110

aperture in the shell, as illustrated in Fig. 1, two of the bracket devices being employed connected with each shelf, as represented in Fig. 2. The shelves are thus detachable to enable them to be packed within the shell for transportation or storage.

Having thus described the invention, what is claimed as new is—

1. A device of the class described comprising a shell, a perforated supporting member resting on the upper surface of the shell, a perforated cut-off plate of less diameter than the supporting member pivotally mounted for rotation on the upper surface thereof, the perforations in the cut-off plate being adapted to register with the perforations in the supporting member and a bail extending transversely across the upper surface of the perforated cut-off plate and provided with depending legs extending through the adjacent perforations in the supporting member and provided with terminal enlarged heads adapted to bear against the lower face of the supporting member when the bail is in elevated position

and to extend within the shell when the bail is in lowered position.

2. A device of the class described comprising a shell open at the ends and adapted to be disposed over a heat radiating medium, flat transverse bars disposed within the shell having their outer ends provided with depending lugs rigidly secured to the inner wall of the shell and their central portions intersecting and rigidly united, said bars being adapted to support a liquid container, a perforated supporting member resting on the upper edge of the shell and provided with a depending flange conforming to and bearing against the inner wall of the shell and a perforated cut-off plate pivotally mounted for rotation on the upper surface of the supporting member, the perforations in the cut-off plate being adapted to register with the perforations in the supporting member to control the draft through the shell.

In testimony whereof I affix my signature.

JAMES D. DUNN. [L. s.]
